(57) **CLAIM**

The ornamental design for a screw-in rosette for a discharge end of a sanitary fitting, as shown and described.

DESCRIPTION

FIG. 1 is a bottom perspective view of a screw-in rosette showing my new design;

FIG. 2 is a top perspective view thereof;

FIG. 3 is a bottom plan view thereof;

FIG. 4 is a top plan view thereof; and,

FIG. 5 is an elevational view thereof.

The broken lines in the Figures are for illustrative purposes only and forms no part of the claimed design.
